UNITED STATES PATENT OFFICE.

MASON L. COPE, OF DENTON, TEXAS.

GATE.

SPECIFICATION forming part of Letters Patent No. 281,026, dated July 10, 1883.

Application filed February 2, 1883. (Model.)

To all whom it may concern:

Be it known that I, MASON L. COPE, of Denton, Denton county, Texas, have invented a new and Improved Gate, of which the following is a full, clear, and exact description.

My invention consists of a gate mounted at the middle on a vertical post pivoted at top and bottom in suitable bearings to enable the gate to swing open and shut on its vertical axis, and one of the bars of the gate is made to serve for the latch by being fitted to rise and fall, and being connected with levers mounted on the central post, and arranged to be conveniently reached by persons riding in carriages to open and close the gate without dismounting, all as hereinafter fully described.

Reference is to be had to the accompanying drawings, forming part of this specification, in which similar letters of reference indicate corresponding parts in both figures.

Figure 1 is a perspective view of my improved gate, and Fig. 2 is a section of the central post.

The gate-bars *a b c* are fitted in a strong vertical post, *d*, which supports said bars at the middle, and is itself supported at its ends in bearings *e* and *f*, in which it is free to revolve for opening and closing the gate. The lower bearing is set in the ground, or may be in a sill, if preferred, and the upper one is in a beam, *u*, mounted on the posts *g*, set in the ground or otherwise fixed in upright position. The middle bar, *b*, is fitted in its mortise *h*, so as to rise and fall freely, to serve for the latch 35 to fasten the gate, making a double latch to fasten at both ends, both of the posts *g* having the requisite notches and latch-strokes, and the same being suitably arranged for latching both ways that the gate swings. The latch-bar has studs *i* working in slots *j* to keep it in position, and it is connected by chains *k* with a couple of levers, *l*, suspended at *m* from a bar, *n*, and jointed together at *o* in the center

of the slot *p*, so that each lever will be operated by the other when pulled down to open 45 the gate. From the outer end of each lever a rod, *q*, hangs within reach of a person on foot or in a carriage. The levers, being thus connected together, are made to act on the latch-bar both sides of the post alike, although they 50 are only connected to said bar at one side of the post—that is to say, one on each side—which is simpler than to connect both levers at both sides of the post, and the bar *b* balances better on the chains.

If desired, the ends of the gate may be connected to the upper end of the central post by stay rods or wires *s*, to prevent the gate from sagging.

It will be seen that the gate balances on the 60 center post, so as to turn very easily, enabling one in a wagon to open it readily by pushing it around with the rod *q*, employed for raising the latch. The arrangement provides a double gate, opening two passages, and by reason 65 of the balance of one side by the other it will not sag, and consequently will be more lasting than gates hanging at one end.

Having thus described my invention, I claim as new and desire to secure by Letters Patent—

1. The combination of levers *l* with the center post, *d*, and the latch-bar *b*, said levers being connected to the latch-bar, and also being connected together in the center of the post, substantially as described.

2. The combination of bar *b*, having guide-studs *i*, with the post *d*, having slots *h* and *j*, said bar being connected to levers *l*, and the post *d*, having the gate mounted on it, and being arranged with relation to posts *b* substantially as described.

MASON L. COPE.
